to all persons to whom these presents shall come:

Be it known that I Winslow Ames of Nashua in the County of Hillsboro, and State of New Hampshire, have invented or produced a new ornamental design for a Portable grate or Fire Place, which I do hereby declare is fully represented in the accompanying drawings of which.

Figure 1. is an elevation, while Figure 2. is a vertical section of the front plate, or parts of the said grate or fire place, the said section being taken on the line a. b. of figure 1.

In such drawings H denotes the hearth plate of the ash pit, A the cover, or lower blower. K the fender or front-plate of the grate I. B is the upper blower. - D, E, F the ornamentation of the front plate C the urn of the top plate L. M is the front plate, and N, N. the legs.

The ornamental design of each of the above parts is exhibited in the drawings with sufficient perfection to enable a skillful Stove Pattern Maker to understand and construct the same.

What I claim is the design of the front of the stove, or more particularly that of the urn, the front plate, the upper blower, the fender, and the lower blower as shown in the drawings.

In testimony whereof I have hereunto set my signature, this twenty fourth day of July,

A.D. 1855.
